UNITED STATES PATENT OFFICE.

RICHARD S. TERRY, OF MILFORD, CONNECTICUT.

GAME APPARATUS.

1,425,617.

Specification of Letters Patent. Patented Aug. 15, 1922.

Application filed May 20, 1921. Serial No. 471,145.

To all whom it may concern:

Be it known that I, RICHARD S. TERRY, citizen of the United States, residing at Milford, in the county of New Haven and State of Connecticut, have invented certain new and useful Improvements in Game Apparatus; and I do hereby declare the following to be a full, clear, and exact description of the invention, such as will enable others skilled in the art to which it appertains to make and use the same.

This invention relates to a game apparatus wherein a board is employed on which are arranged a series of disappearing plates bearing or temporarily concealing certain characters comprising the game.

Referring to the accompanying drawings wherein the same numerals and letters of reference indicate like characters throughout the several views;

Figure 1 represents the game board showing the plates in their normal position with an indicator dial connected therewith;

Figure 2 is an enlarged broken sectional view of the game board showing the first plate at the left in its normal position, the second plate in the act of passing through an opening in the board, and the third plate with the principal part thereof below the upper surface of the board;

Figure 3 is an enlarged detail view in perspective of one of the plates, and

Figure 4 is an enlarged broken view of the board showing one of the plates in its normal position covering the characters pertaining to the game, and showing the other plate retreated and its previously underlying characters exposed to view.

The board *a* has on its upper margin the capital letters A to H inclusive, each letter being located over its individual line of plates below said letters. On the left hand margin of the board, each in line with a horizontal row of plates, are the numerals 1 to 6 inclusive.

b is a stationary dial, mounted on the extension *c* of the board, carrying the indicator *d* journaled on the central stud *e*. This dial is divided into sectors bearing the same capital letters represented in the upper margin of the board. In the margin of each sector are duplicate numerals of those shown on the left hand margin of the board.

f represents the several plates all of which are alike as to details of construction and are shown to better advantage in the en-

larged views in Figures 2, 3, and 4. The upturned ends *g* of the plates serve both as means to raise them from a horizontal position and also to prevent their falling through the opening *h* in the board when reversed. The opposite ends of the plates have the angular opposed bends *i* provided with the retaining ears *j* adapted to contact with the underside of the board to prevent their being detached from the board when transferred from their vertical position to their horizontal or normal position.

The manner of playing the game in accordance with the construction and arrangement shown in Figure 1 is as follows:

The number of plates correspond to the number of States from Maine to California, each plate bearing the name of a particular State and the number representing its electoral vote. Each player will make his choice of the Presidential candidate he favors, and each, in turn, will give the pointer a sudden whirl and wherever it stops, it will determine the result to be obtained from the board. Referring to the dial *b*, it will be noted that the indicating end *k* of the pointer has come to rest in the sector G and opposite the numeral 5. Referring to the board for the result, the player will note that the intersection of an imaginary vertical line drawn from G in the upper margin and a horizontal imaginary line drawn from the numeral 5 in the margin at the left, will indicate the State of Wyoming, with its three electoral votes, to be placed to his credit, and will raise said plate from its normal position and drop it through its opening in the board with the part *g* resting on the upper surface of the board as shown in Figures 2 and 4. The next player will repeat the process, note the result in his favor, and also remove his plate. Each player will thus alternate until one has registered enough electoral votes to elect his candidate, and is declared the winner. As many players can participate in the game as there are candidates in the field.

In Figure 4, the plates are devoid of characters which are located on the board to be disclosed when said plates are lifted. The different characters are preferably attached to either the plates or the board so that others can readily be substituted, as, for instance, in the electoral game when a change in the electoral vote of any State is made.

The temporary removability of the

plates as a necessary feature in a game will permit the use of a variety of characters that may be employed either in a game or puzzle.

5 When a game is finished, the plates that have been dropped into the openings can easily be made to re-assume their normal positions on the board by simply turning the board over and thus cause the plates to 10 hang vertically with their ears ; engaging the underside of the board, when a quick horizontal movement of the board will relay the plates.

Having thus described my invention, what 15 I claim is;

1. A game apparatus comprising a board having a series of individual openings therethrough arranged in horizontal and transversal rows, plates associated with said 20 openings and adapted to normally assume a horizontal position on the board, and also adapted to be inserted in the openings into a vertical position, one end of the plates having means adapted to engage the board 25 and maintain said plates in such vertical position, and means at the opposite end of the plates adapted to engage the underside of the board to prevent disengagement of said plates with respect to the board.

30 2. A game apparatus comprising a board having a series of individual openings

therethrough, plates associated with said openings and adapted to normally rest against the upper surface of the board, and be temporarily inserted into said openings, 35 one end of the plates having an angular bend adapted to engage the upper surface of the board when said plates are inserted in said openings, the opposite ends of the plates having reverse bends with extended 40 ears adapted to engage the under surface of the board to prevent the plates being detached therefrom when said plates are in a normal position.

3. A game apparatus comprising a board 45 having a series of individual openings therethrough, plates associated therewith and adapted to be inserted in said openings and be temporarily concealed below the board, said plates arranged in horizontal 50 and transverse rows having characters thereon representing the several States and their electoral vote, characters in the margins of the board for locating any particular character bearing plate, a dial having 55 characters thereon corresponding to the characters in the margins of the board, and a pointer adapted to have a free movement around said dial.

In testimony whereof I affix my signature. 60

RICHARD S. TERRY.
